UNITED STATES PATENT OFFICE.

LAURITZ W. ANDERSEN, OF WATERBURY, CONNECTICUT, ASSIGNOR TO GENERAL ELECTRIC COMPANY, A CORPORATION OF NEW YORK.

SOCKET-SHELL.

1,193,966.

Specification of Letters Patent.

Patented Aug. 8, 1916.

Application filed March 3, 1915. Serial No. 11,728.

To all whom it may concern:

Be it known that I, LAURITZ W. ANDERSEN, a citizen of the United States, residing at Waterbury, in the county of New Haven 5 and State of Connecticut, have invented a new and useful Socket-Shell, of which the following is a specification.

This invention relates generally to socket shells for covering the porcelain portion of 10 an incandescent lamp socket, and the object of the invention is to provide a simple and safe means for connecting the cap and body portions of the said socket shell.

Another object of the invention is to provide 15 a socket shell of such construction that it can be used for either key, keyless, pull chain, or push button sockets and switches, and a still further object is to provide a 20 socket shell in which the parts can be quickly and easily assembled without the aid of skilled labor.

With these objects in view my invention 25 consists in constructing a socket shell of three parts, namely, a cap threaded at its lower end, a body portion adapted to telescope 30 into the said cap portion, and a ring carried by said body portion and adapted to engage the lower end of the cap and securely hold the body portion against longitudinal 35 movement.

The invention consists also in certain details of construction hereinafter fully described, and pointed out in the claims.

In the drawings forming a part of this 35 specification, Figure 1, is a perspective view partly in section showing a socket shell constructed in accordance with my invention. Fig. 2, is a sectional view of the cap, Fig. 3, is a sectional view of the collar, or ring, and 40 Fig. 4, is a sectional view of the body portion or bottom of shell.

In the practical embodiment of my invention I employ a cap A, which has the usual bushing at the top and is made very much 45 the same as cap portions now in use except that this cap A has a slightly longer skirt portion which is reduced and threaded at its lower end as shown at A', and providing a perceptible shoulder A².

50 The body portion B is formed with the usual bead B' at the lower end thereof, and the upper end of the body portion is fitted up into the cap as most clearly shown in Fig. 1, and for the purpose of securing the cap

portion and body portion together, I employ 55 a collar C, which is arranged upon the body portion above the bead B' and below a smaller bead B², the longitudinal movement of this collar being limited by the bead B² at the top, and by the bead B' at the bottom, 60 but it will be understood that the collar turns freely upon the said body portion. The lower end of the collar is beaded and milled as shown at C' and its upper end is threaded 65 as shown at C², and this collar is formed with an internal shoulder C³, which engages the bead B², and thereby prevents the collar and body portion from being disconnected.

When the upper portion of the body B is 70 telescoped into the cap the collar C is securely connected to the lower end of the cap by screwing the threaded portions together, and inasmuch as the collar contacts with the intermediate bead 75 of the body portion it will securely hold the body portion against longitudinal movement. When the upper edge of the collar contacts with the shouldered portion A² of the cap further rotation will be stopped, and 80 the parts will be securely connected together and it will be understood that the operation of connecting these parts can be quickly and easily accomplished without use of skilled labor. It will also be understood that the 85 several parts of the socket shell can be varied slightly in regard to details of construction, so long as such variations fall within the scope of the appended claims.

What I claim is:

1. A socket shell comprising a cap having 95 a skirt, a cylindrical body portion having a bead intermediate its ends, and also a bead adjacent its lower end, and a collar arranged upon the body portion between said beads, 95 said collar and lower end of skirt of cap being provided with engaging means, whereby said parts are connected together.

2. A socket shell comprising a cap having 100 a skirt, the lower end of said skirt being threaded, a cylindrical body portion having a bead intermediate its ends and also a bead adjacent the lower end, and a collar on said body portion between said beads, said collar being threaded and adapted to engage 105 the threaded end of skirt, the upper end of body extending into said skirt.

3. A socket shell comprising a cap having

a threaded lower end and a shoulder at the upper end of said threaded portion, a body portion having a bead intermediate its ends and also a bead adjacent its lower end, the upper portion of said body being adapted to fit into the cap, and a collar arranged upon the body portion between the beads, said collar being turnable upon the body and having a shoulder adapted to engage the

intermediate bead, the upper portion of said collar being threaded and adapted to engage the threaded portion of the cap whereby said cap and body portions are connected together.

LAURITZ W. ANDERSEN.
